UNITED STATES PATENT OFFICE.

CHARLES J. SIBBALD, OF WATERFORD, NEW YORK.

STITCH-FORMING MECHANISM FOR SEWING-MACHINES.

1,118,450.

Specification of Letters Patent. Patented Nov. 24, 1914.

Application filed March 12, 1908. Serial No. 420,609.

To all whom it may concern:

Be it known that I, CHARLES J. SIBBALD, a citizen of the United States, of Waterford, in the county of Albany and State of New York, have invented certain new and useful Improvements in Stitch-Forming Mechanism for Sewing-Machines; and I hereby declare that the following is a full, clear, and exact description of the same, reference being had to the accompanying drawings, forming part of this specification.

This invention relates to improvements in sewing machines and particularly to improved stitch forming mechanism therefor.

One object of this invention is to so construct stitch forming means for sewing machines that the needle thread may be held while loops of said needle thread are successively formed and passed around such held portion.

Another object of this invention is to so construct stitch forming means for sewing machines that the needle thread, carried downward by an initial stroke of the needle may be so engaged that its movement toward the work is resisted while loops successively formed in said needle thread are passed around such engaged portion and such portion is permitted to be drawn, by the said successive loops, into or against the work.

Another object of this invention is to so construct stitch forming means for sewing machines that the needle thread carried toward the looper by an initial stroke of the needle may be frictionally engaged and that sufficient thread may be drawn from the needle thread supply to provide an under thread supply for the sewing operation.

The invention consists in the peculiar features of construction and combination of parts whereby the objects of the invention are carried into effect as shall hereinafter be more fully described and pointed out in the claims.

Figure 1, represents an elevation, partly in section, of portions of a sewing machine illustrating the new invention. Fig. 2, represents a sectional view thereof taken on line 2-2 Fig. 1. Fig. 3, represents a view similar to parts of Fig. 1 to illustrate the engagement of the end portion of the needle thread by the hook, parts of the machine being shown in section. Fig. 4, represents a view taken at right angles to Fig. 3. Fig.

5, represents a bottom plan view of the machine showing the hook driving means and the means for effecting the opening of the thread clamping device. Fig. 6, represents 60 a view of the thread clamping device and the hook, in which view the hook is shown as drawing down the end portion of the needle thread to provide an under thread supply and to draw said thread into the 65 clamp. Fig. 7, represents a sectional view of the clamp and the hook, the clamp being held in the open position as when the thread is in position shown in Figs. 6 and 8. Fig. 8, represents the parts shown in Fig. 6 with 70 the cut end of the needle thread drawn between the parts of the thread clamp. Fig. 9, is a top plan view of the clamp with its hinged member closed to engage the needle thread when said thread is carried to or 75 approximately to the position shown in Fig. 8. Fig. 10, represents a view of the parts shown in Fig. 8, with the hook positioned to cast off a loop of the needle thread around the held portion of the same thread. 80 Fig. 11, represents the stitch formed by this mechanism in continuous sewing.

Similar numbers of reference designate corresponding parts throughout.

As shown in the drawings, in its preferred form 15 represents the usual needle bar of any ordinary sewing machine, the operating parts of which are well known, and 16 is the needle to which the thread *a-b* is supplied in the ordinary manner. 85

The bed plate 17 has the usual opening 18 above which extends the throat plate 19, having the needle hole 20. At the under side of the bed plate is journaled the drive shaft 21 adapted to be driven in any ordinary manner and having the worm 22 and a driving connection with the journaled shaft of the bevel gear 23. Motion is transmitted from the gear 23 by means of the idle gear 24 to the gear 25 mounted on the 95 tubular hook-driver-shaft 26 which is journaled in bearings and has the usual hook driver 27 rotatable within the casing 28 and engaged in the ordinary and well known manner with the hook 29 rotatably supported within said casing. The plate 30 of said hook 29 has the axially disposed perforated hub 31 having the reduced portion 32, Figs. 2 and 7, furnished with a screw threaded bore into which the 100 perforated reduced shank of the perforated button 33 is screwed. The reduced portion 110

or neck 32 of the hub 31 is rotatably engaged in the collar 34 of the clamp member 35, and is held from longitudinal movement therein between the button 33 and the larger diameter of said hub. Said clamp member 35 has a central chamber, to receive said button 33, and is furnished with the pin sockets 36 and 37 and lip 38. And hinged to said member 35 by a spring closed hinge, Fig. 9, is the complemental clamp member 39 having the pins 40-41 on its inner face, adapted to be received by the sockets 36 and 37, and, on its outer face the pin 42 while in a screw thread perforation in said member 39 is engaged the screw 43. Within the bore of the buttons 33 is movable the plunger 44 having a reduced portion which extends into the bore of the hub 31.

The thread clamping device and its collar 34 is held from rotation by the arm 45 pivotally mounted on the lower part of the casing 28 and having fingers 46 at its free end which engage the pin 42 of the clamp member 39, the usual latch 47 being provided on said casing 28 to lock the arm 45 in the position for engaging said pin 42. On the upper part of said casing or other fixed part of the machine is mounted the pin 48 which extends toward the upper end of the clamp member 35 and hence extends above the path of the hook.

In the perforation of the shaft 26 is slidably mounted the rod 49 having an extension which is free to enter the perforation of the hub 31, see Figs. 2 and 7, to act against the plunger 44, when this rod 49 is forced inward against the action of its retracting spring 50 located on said rod between a cross pin fixed to the rod and a fixed portion of the machine. Means are provided for intermittently sliding said rod 49 inward against the action of the spring 50 to press forward the plunger 44 against the clamp member 39 whereby said member is swung outward from its complemental member 35 against the closing pressure of its closing spring. Such means are shown in Fig. 5 of the drawing and preferably comprise the usual button clamp vibrator cam 51 journaled on a stud extending from the bed plate of the machine and having the gear 52, meshing with the worm 22 of the main shaft, and the cam 53 so adjustably mounted on the cam 51 that, at a predetermined point in the sewing operation or initial thereto, said cam 53 is brought to position to act on the bearing 54 of the bell crank lever 55 which is pivotally mounted in the machine and has a member which bears against the outer end of the rod 50 whereby at such predetermined point said rod 50 is pushed inward to actuate the plunger 44 and is held inward during the movement of the highest portion of the cam 53 past the bearing 54.

The method of operation of this improved stitch forming mechanism as described herein refers more particularly to the sewing of comparatively few stitches considered as a group as, for instance, in the sewing on of buttons. Nothing herein however is to be considered as a limitation to any particular class of sewing and obvious variations from the specific description are necessarily understood as, for instance, it is well known that in lock stitch sewing it is necessary to supply sufficient under thread, for the number of stitches to be sewn and it is to be presumed that the length of the under thread or its equivalent herein referred to as such, is sufficient for the sewing operation under consideration.

Before the sewing operation the thread *a* is drawn through the needle to provide the end *b* as is usual to prevent the end of the thread from drawing back through the eye of the needle on the first downward stroke of the needle; this end *b* may however be considerably longer than usual.

The mechanism is so timed as to its operation that as the initial downward movement of the needle is made the cam 53 acts on the bearing 54 of the lever 55 to swing said lever and force inward the rod 49 the reduced portion of which presses forward the plunger 44 which effects the swinging outward of the clamp member 39 against the action of its closing spring. When now the needle has moved down approximately to the point shown in Fig. 3 the hook 29 engages the loop 100 of the end *b* of the thread *a* and, in the movement of said hook, draws on said loop, opening said loop and drawing it downward. Under said drawing action of the hook the thread *a* is also somewhat drawn down through the eye of the needle unless the tension on said thread is more than sufficient to overcome the frictional resistance of the work, through which the end *b* is drawn, on said end. After the engagement of the hook 29 with a loop of the thread said hook first carries the loop toward the spreader 48 which guides one arm of said thread loop back of the hook carrier. This feature being of more particular importance to the second and subsequent loops than to the first loop as will hereafter be explained.

The continued rotation, or movement, of the hook 29 now effects the drawing of the end *b* of the thread downward as is shown in Fig. 6 and over the extension 38 of the clamp member 35 which assists in guiding said thread *b* between the clamp members 35 and 39, approximately as shown in Fig. 8 at which time said thread is intercepted by the pin 41 of said clamp. At or about this time the cam 53 passes the bearing 54 of the lever 55 and the spring 50 acts to retract the rod 49 and permit the closing of the clamp member 39 under the tension of

its spring whereby the thread *b* is engaged between said clamp members and is held under tension thereby.

At the second and subsequent downward movements of the needle the thread loop taken by the hook 29 is carried around said clamp one arm of said loop being guided by the spreader 48 back of the hook carrier 30 passes between the ends of the plunger 44 and rod 49. These successive loops pass around the thread clamping device as indicated in Fig. 10 and, from approximately the point indicated in said figure, are cast off and are drawn upward by the usual and well known thread take up and the upward movement of the needle until said loops are drawn around the thread extending from the work to the clamp and said drawing action is preferably continued until the thread held under tension by said clamp is drawn out sufficiently to form its part of the stitch, and the sewing operation proceeds as in any ordinary sewing machine supplied with upper and under thread. For, in effect, the thread clamp 35-39 assumes the function of an under thread holder and yields said thread as the stitches are formed in succession.

It is to be noted that the thread clamping device 35-39 is preferably held from rotation, during the sewing of the second and subsequent stitches, by means of the arm 45 having its fingers 46 engaging the pin 42 of the clamp member 39, but this invention is not necessarily limited thereby to such a thread clamping means held from movement for if the arm 45 was released from the pin 42, after the closing of said clamp the frictional engagement of the hub 32 on the collar 34 of said clamping device would tend to rotate said clamp and effect the drawing downward of an additional supply of under thread which would be wound around the clamp. But it is apparent that the preferred means for drawing downward of the needle thread to furnish an under thread supply is through the medium of the hook moving with respect to the clamp.

The term "hook" is herein used as particularly descriptive of the device shown but reference to such term includes any device of this nature however operated which acts to draw the thread in order to assist in forming a loop or for the purpose of drawing down the needle thread to provide a

supply of under thread. Nor is this invention limited to the use of a rotary hook or looper.

Having thus described my invention I claim as new and desire to secure by Letters Patent.

1. Stitch forming means for sewing machines comprising a needle, a spring closed thread clamp located below the needle, means actuated by the driving means for opening said clamp and for permitting it to close after a period of time, and a looper hook rotatable with respect to said clamp.

2. Stitch forming means for sewing machines comprising a rotatable looper, a thread clamp located below the work and having a spring closed member extending approximately to the path of said looper, means operated through the driving mechanism for opening said member against its spring, said means including a member adapted to be retracted before the formation of a closed loop.

3. Stitch forming means for sewing machines comprising a thread clamp a looper journaled in a bearing in said clamp and carrying clamp opening means, means for holding said clamp from movement, and means for actuating said clamp opening means.

4. Stitch forming means for sewing machines comprising a two part spring clamp having a collar, a perforated hub journaled in said collar, a clamp opening plunger slideable in said perforation, a loop hook mounted on said hub, means for holding the clamp from movement, and means for actuating said plunger at times to open the clamp.

5. In stitch forming means for sewing machines, a thread clamp comprising one member furnished with a bearing and having a thread guiding lip at its lower portion, and a member hinged to said first member and having a spring acting to close the same and a screw for regulating the closing thereof, means for holding said clamp from movement, a hub journaled in the collar of the first mentioned clamp member, a looper mounted on said hub, and clamp opening means slideable in a perforation of said hub.

CHARLES J. SIBBALD.
